CLAIM

The ornamental design for a transparent scalpel blade support element with universal blade fitting as shown and described.

DESCRIPTION

FIG. 1 is a perspective view of a transparent scalpel blade support element with universal blade fitting showing my new design;

FIG. 2 is a right side view of the transparent scalpel blade support element with universal blade fitting;

FIG. 3 is a left side view of the transparent scalpel blade support element with universal blade fitting;

FIG. 4 is a top view of the transparent scalpel blade support element with universal blade fitting;

FIG. 5 is a bottom view of the transparent scalpel blade support element with universal blade fitting;

FIG. 6 is a rear view of the transparent scalpel blade support element with universal blade fitting;

FIG. 7 is a front view of the transparent scalpel blade support element with universal blade fitting; and,

FIG. 8 is a front perspective view of transparent scalpel blade support element with universal blade fitting as attached to a handle.

The broken lines in FIG. 8 illustrate environmental subject matter that forms no part of the claimed design.
